UNITED STATES PATENT OFFICE.

MARK ANTHONY, OF NEW YORK, N. Y., ASSIGNOR TO THE DIAMOND MATCH COMPANY, OF CHICAGO, ILLINOIS, A CORPORATION OF ILLINOIS.

INKING-ROLLER FOR PRINTING-PRESSES.

No. 801,171.

Specification of Letters Patent.

Patented Oct. 8, 1905.

Original application filed September 10, 1896, Serial No. 605,347. Divided and this application filed January 12, 1905.
Serial No. 240,744.

To all whom it may concern:

Be it known that I, MARK ANTHONY, a citizen of the United States, and a resident of the city, county, and State of New York, have invented 5 certain new and useful Improvements in Ink-rollers for Printing-Presses, of which the following is a specification.

This application is a division of an application filed by me September 10, 1896, Serial 10 No. 605,347, for certain improvements in printing-presses more especially designed for printing upon the sides of match-splints or the like.

The subject of the present application is an 15 inking-roller of simple and efficient construction, whereby a regular and uniform flow and supply of ink to the type is effected, as will hereinafter appear.

In the drawings, Figure 1 is a plan of the 20 inking-roller and a portion of a type-wheel engaging the same. Fig. 2 is a longitudinal vertical section of the roller. Fig. 3 is a transverse section thereof.

L represents a portion of one of the type-wheels of a printing-press, and X the inking-roller with which the wheel engages. This roller comprises a hollow cylinder or shell constituting an ink-reservoir, having at its ends trunnions x^1 , by which it is rotatably supported in standards N. Surrounding this cylinder or shell is a covering x^1 of fibrous or other material having capillary interstices—such, for example, as felt. Piercing the wall of the shell at several points, so as to place its 35 interior in communication with the fibrous covering, are openings x^2 , which are inclined from radial lines, so as to facilitate the passage therethrough of the fluid ink contained in the reservoir. The inclination of the perforations, 40 as shown in Fig. 3, is outward and rearward with reference to the direction of rotation of the roller, and this arrangement is relied upon

to facilitate the passage of the ink from the reservoir to the exterior absorbing material. It will be understood that if these openings 45 were arranged radially the only force present tending to cause the ink to flow through them would be centrifugal force, owing to the consistency of the ink and the want of sufficient capillary attraction of the openings. When, 50 however, these openings are arranged as described, inertia acts in conjunction with centrifugal force to cause the desired flow of ink, for the reason that as the roller moves more rapidly than the ink within it the openings 55 take up the ink by a scooping action and facilitate its movement outward. Four openings are shown; but this number may be increased or diminished. One end of the roller is in the form of a removable head secured in place 60 by pivot-latches x^3 .

I claim—

1. An inking-roller having an internal reservoir from which perforations extend outwardly that incline from lines radial to the 65 center of the roller, substantially as described.

2. In an inking-roller, the combination of an absorbent exterior surface and an interior shell forming an ink-reservoir, the wall of said shell being provided with perforations that incline 70 from lines radial to the center of the roller, substantially as described.

3. In an ink-roller, the combination of an absorbent exterior surface and an interior shell forming an ink-reservoir, the wall of said shell 75 being provided with perforations that are inclined from radial lines and outward and rearward relative to the direction of travel of the roller, substantially as described.

MARK ANTHONY.
